FINISHING MACHINE FOR EMBLEMATIC BUTTONS.
APPLICATION FILED NOV. 5, 1918.

Patented Dec. 23, 1919.

2 SHEETS—SHEET 2.

UNITED STATES PATENT OFFICE.

EDWARD T. MASSEY, OF NEW YORK, N. Y.

FINISHING-MACHINE FOR EMBLEMATIC BUTTONS.

1,325,526.

Specification of Letters Patent. Patented Dec. 23, 1919.

Application filed November 5, 1918. Serial No. 261,216.

To all whom it may concern:

Be it known that I, EDWARD T. MASSEY, a citizen of the United States, residing at the city of New York, borough of Queens, and 5 State of New York, have invented certain new and useful Improvements in Finishing-Machines for Emblematic Buttons, of which the following is a full, clear, and exact description.

10 My invention has reference to a machine for finishing emblematic buttons.

In an application filed concurrently herewith, I describe a method of making emblematic buttons from sheets of paper, and 15 ordinary straight pins of the type commonly used in dressmaking. The pins are subjected to various bending operations during the manufacture of the button until they finally assume the requisite U-shaped form.

20 The machine which forms the subject matter of this application accomplishes the bending of the pins in a substantially automatic manner, and automatically alines the pins prior to the bending so that they point in the 25 proper direction.

The drawings accompanying this specification show one embodiment of my invention, in which—

Figure 1 is a fragmentary side elevation 30 of my apparatus.

Fig. 2 is a top plan view of the apparatus partly in section.

Fig. 3 is a section of Fig. 2 on the line 3—3.

35 Fig. 4 is a section of Fig. 2 on the line 4—4, and

Fig. 5 is an enlarged fragmentary detail view of some of the elements of my apparatus.

40 In the drawings, the bed or foundation of the apparatus is indicated in its entirety by the reference character 10 and comprises two substantially identical side frames 11 and 12 placed in spaced relation. The upper 45 central portion of each of the side frames 11 and 12 is thickened at 13, to form a bearing for journals 14 extending from each side of a tray supporting roller 15. A plurality of bearings 16 are provided on the upper surface 50 of each of the side frames 11 and 12 to carry the journals 17 of rollers 18. The rollers 15 and 18 form a rolling bed for a tray, which will be described. Each of the side frames 11 and 12 have an upwardly projecting bracket 19, preferably located directly over the journals 14. Each of the brackets

19 has a central opening or groove 20 adapted to receive a vertically movable pillow block 21, and they are connected to each other by a span 22. The pillow blocks 21 support journals 23 and 24 which extend from each side of a main presser roller 25. The journal 24 is extended beyond its bearing and is provided with a worm gear 25'. A bracket 26 extends laterally from the side 65 frame 12 and supports a rotatable worm 27, which meshes with the worm gear 25'. The worm may be actuated by any suitable source of motive power which may be thrown in and out by suitable control means. The 70 main roller 25 accomplishes the final bending of the pins and the pressing of the buttons. An adjusting screw 28 passes through each end of the span 22 and bears on the upper surface of each of the pillow blocks, 21, 75 while a spring 29 bears against the lower face of each of said blocks and exerts its pressure in a direction contrary to that of the screw 28. The spring 29 provides a yielding support for the block 21, which is 80 thereby enabled to move downward while its upward movement is definitely limited by the screw 28. The main presser roller 25 is provided on each end thereof with peripheral gears 30. A yoke or bridging member 31 has an end connected to each of the side frames 11 and 12 and extends across the machine in front of the main presser roller 25 and preferably substantially parallel therewith. The yoke 31 is provided 85 with a plurality of downwardly depending screws 32, each of which is formed so as to provide a bearing 33 at its lower end, and having a shouldered portion 34 adapted to abut against the lower surface of the yoke. 90 A roller 36 is journaled in the bearings 33, and extends across the machine in front of and parallel to the main roller 25. This roller accomplishes the preliminary bending of the pins, as will appear hereinafter. Plates 37, having a plurality of slots 38, rest on the upper surface of the yoke 31 and are held in place by the screws 32, which have their shanks located in these slots. The slots permit movement of the plates 37 relatively to the yoke 31. A downwardly depending swinging plate 39 is hinged to each of the plates 37 and in turn supports a plate or curtain 40. This curtain is provided with a plurality of vertical slots 41 preferably 100 evenly spaced and of sufficient height to permit the pins of the unfinished buttons

to pass therethrough. These vertical slots divide the lower portion of the depending curtain into a plurality of blades 42, to the lower ends of the side blades of which there are connected forwardly projecting extensions 53, and to the lower ends of each of the remaining intermediate blades 42 there is connected a forwardly projecting guide finger 43, having a beveled lower face 44, and terminating in a triangular-shaped nose 45. The front ends of the extensions 53 are connected by the cross arms 54. Any pins of the unfinished buttons which may not be properly alined, strike this nose and are thereby forced into the proper position (i. e. are alined). When inserting the work 52, the frames formed by the extensions 53 and cross arms 54 are first tilted upward, thereby tilting upward the fingers 45 with them, and upon the work 52 having been properly placed, the frames are then brought down upon the edges of the work as shown in Fig. 2. The tilting of the frames together with the fingers 45 is also of value in facilitating the removal of foreign material collecting between the roller 36 and the fingers 45. The strap or brace 46 may connect the span 22 with the yoke 31 to prevent vibration thereof. A slidable tray 47 adapted to ride on the supporting rollers 15 and 18 is provided on two opposite edges with guide flanges 48 bolted thereto, each of which have rack teeth 49 formed on their upper edge, which mesh with the peripheral gears 30 of the main presser roller 25. The tray 47 is longitudinally moved by the rotation of these gears. The lower end of each of the flanges 48 projects below the tray 47, forming guide rails which abut against the side 40 of the supporting rollers 15 and 18, journaled in the side frames, and prevents lateral movement of the tray. The tray 47 is adapted to receive a platen 50 carrying the work 52 to be operated upon.

45 My apparatus operates as follows:

A suitable platen as 50, carrying a blank of work 52, containing the partially finished buttons and having the pins in rows, is placed on the tray 47. The worm 27 is rotated by suitable control mechanism, and the worm gear 25 actuated thereby rotates the main presser roller 25. The peripheral gears 30 on said roller, by engagement with the rack teeth 49 move the tray 47 transversely with respect to this roller. The upwardly extending rows of pins of the unfinished buttons which are not in alinement in the course of the movement of the tray 47 strike the pointed noses 45 of the guide fingers 43, and the pins are forced into alinement thereby. The pins then pass through the slots 41. Each row of pins now points in the same direction (i. e. they are alined). A further movement of the tray

47 carries the platen 50 under the roller 36, 65 which partially turns down the pins. The pins then pass under the main roller 25, which bends the pins to their final position, and firmly unites the sheets of paper comprising the button. The buttons are then 70 ready to be removed from the blank, and are in their finished form.

I claim:

1. In a machine for finishing emblematic buttons, the combination of means for 75 alining the pins of the unfinished button, and means for bending the pins to their required position.

2. In a machine for finishing emblematic buttons, the combination of means for alining the pins of the unfinished buttons, 80 means for bending the pins, and means for progressively carrying the buttons into operative relation with each of said means.

3. In a machine for finishing emblematic 85 buttons, the combination of means for alining pins of the unfinished buttons, sliding means adapted to carry the pins through the alining means, and means for bending the alined pins.

4. In a machine for finishing emblematic buttons, the combination of a frame, means for alining the pins, a sliding tray movable in said frame and adapted to carry an assemblage of unfinished buttons having upwardly projecting pins through said alining means whereby the pins are caused to point in the same direction, and means for bending the pins to their required position.

5. In a machine for finishing emblematic 100 buttons, the combination of a roller, a plurality of guide fingers each having a pointed nose and sufficiently spaced from each other to permit passage of the pins of the buttons between each pair of fingers, and means to 105 carry the pins of the unfinished buttons between said fingers, and in a direction substantially parallel with the longitudinal axis of the fingers and into operative relation with said roller.

6. Mechanism for alining the pins of unfinished buttons, comprising a plurality of parallel guide fingers, each having a pointed nose and spaced from each other to permit passage of the pins between each pair of 115 fingers.

7. Mechanism for alining the pins of unfinished emblematic buttons comprising a swinging curtain having a plurality of blades spaced from each other, a guide finger 120 having a pointed nose secured to each of said blades.

8. In a machine for producing emblematic buttons, the combination of a frame, means to aline the pins of the unfinished buttons, 125 comprising a downwardly projecting swinging curtain having a plurality of forwardly projecting guide fingers in spaced relation,

and slotted openings between said fingers, a roller coöperating with said means to partially bend the pins to an inclined position, a main roller located behind said last named 5 roller to bend the pins to their required position, and a tray movable relative to said means and adapted to carry the unfinished

buttons between said fingers, through said slots, and progressively into operative relation with the rollers.

In witness whereof I subscribe my signature.

EDWARD T. MASSEY.
